No. 888,821.

PATENTED MAY 26, 1908.

J. A. KLEINE.
SANITARY TOILET SEAT.
APPLICATION FILED MAY 27, 1907.

UNITED STATES PATENT OFFICE.

JOHN A. KLEINE, OF CHICAGO, ILLINOIS.

SANITARY TOILET-SEAT.

No. 888,821.

Specification of Letters Patent.

Patented May 26, 1908.

Application filed May 27, 1907. Serial No. 375,787.

To all whom it may concern:

Be it known that I, JOHN A. KLEINE, a citizen of the United States, residing at Chicago, in the county of Cook and State of Illinois, have invented new and useful Improvements in Sanitary Toilet-Seats, of which the following is a specification.

The object of this invention is to provide a sanitary covering for water closet seats to 10 prevent contagion and otherwise protect the user.

More particularly, the object is to provide a package of the sanitary coverings which can be suitably suspended adjacent to the 15 closet and so that when a covering is detached from the package it will at the same time be torn to remove a stub and adapt the covering for proper application to the seat.

In the accompanying drawings Figure 1 is a 20 perspective view showing a package of the coverings suspended from the side wall of a closet compartment. Fig. 2 is a detail perspective view of the holder cap. Fig. 3 is a detail perspective view of the end of the 25 holder. Fig. 4 is a plan view showing the covering applied to a closet seat. Fig. 5 shows the blank. Fig. 6 shows the blank folded. Fig. 7 is a perspective view of a 30 package of the coverings. Fig. 8 shows the covering opened and before it is torn. Fig. 9 is a sectional view on the line 9—9 of Fig. 4. Fig. 10 is a top plan view showing another 35 means for suspending the package. Fig. 11 is a front elevation of Fig. 10.

In practice I provide a blank 11 consisting 35 of a sheet 12 (Fig. 5) of tissue or other suitable paper or material of a size to form a covering for the seat and folded twice upon the lines 13 and 13' as shown in Fig. 6. A number 40 of folded sheets are arranged in a package and then the package is cut in a suitable manner to provide each sheet with elongated radial openings 14 (Fig. 8) on the lines of fold and a central stub section 15. The package 45 of coverings may be fastened together by a staple 16 passing through holes 17 in the stubs (Figs. 7, 8) or by stitching through the stubs.

The package is suspended in a suitable 50 manner on the side wall 18 of a closet compartment and in the drawings I have shown a simple suspension means which consists of a holder made in the form of a housing 19 shaped to receive the stubs 15 and carried by 55 a plate 20 which is fastened to the wall.

The housing has a slot 21 in its lower edge to accommodate the neck 22 of the coverings (Fig. 7) and the package is held in place in the housing by a cap 23 on the end thereof (Fig. 2). This cap is provided with a revolvable locking plate 24 on its inner side and a handle 25 on its outer side connected to the locking plate, and the plate has projections 26 which enter recesses 26' (Fig. 3) in the inner walls of the housing to lock the cap in 60 place.

In Figs. 10 and 11 I have shown another suspension means which comprises a rod 27 carried by a wall plate 28 and having a removable screw head 29. The holes 17 (Fig. 70 8) in the stub section aline when the sheet is folded and a package of these sheets may be fastened by a staple 16 or by a wire running through these holes. In this adaptation of the invention the staple may be removed and the package slipped on to the rod 27 and secured in place by the screw head 29. If the package is stitched or wired the holes will be left free to receive the rod. I prefer to provide the plate 28 with guides 30 adjacent to 75 the rod 27 to engage the lower inclined edges 15' of the folded sheet and prevent the package and the individual sheets thereof from swinging laterally on the rod. These guides, in the construction shown in Figs. 10 and 11, 80 correspond in practical effect to the lower sides 19' of the housing shown in Fig. 1.

A sheet can be readily detached from the package for use by pulling down on it sufficient to tear the sheet at the neck 22 and 90 separate it from the stub 15 which remains in the housing 19 or on the rod 27. The sections 31 of the sheet between the openings 14, which sections have been connected at their inner ends by the stub 15, will be disconnected 95 when the stub is thus removed from the sheet to form flaps which will swing down within the opening 32 of the seat 33, as shown in Figs. 4 and 9.

The openings 14 may be variously formed 100 in the sheet, it being only essential that they shall be so arranged as to provide a plurality of flaps which are held together at their inner ends by the stub while the sheet is suspended, which stub is separated from the sheet when 105 the latter is detached from the package for use so that the flaps may swing freely down into the opening of the closet seat.

The invention is simple in character and 110 constitutes an inexpensive and effective sani-

tary covering for closet seats which will completely protect the user from direct contact with the seat.

What I claim and desire to secure by Letters Patent is:

A sanitary covering for water closet seats consisting of a sheet folded twice upon itself and provided with a plurality of radial openings to form flap sections therebetween, and 10 a stub section connecting the inner ends of

said flap sections to be engaged by means for suspending the sheet, whereby said stub section will be detached from the sheet when the latter is removed from said suspension means for use.

JOHN A. KLEINE.
